CONTINUOUS TRAIN CONTROL CORPORATION, OF DETROIT, MICHIGAN, A CORPORA-
TION OF MICHIGAN.

AIR-BRAKE-CONTROL MECHANISM.

Application filed December 8, 1926. Serial No. 153,258.

This invention relates to means for automatically discharging the pressure in train pipes of railway rolling stock equipped with air-brakes of the Westinghouse type, and its object is to provide an air-brake control device which will cause the escape of a predetermined portion of the train-pipe pressure when electric current ceases to pass over a selected control circuit. 10 This control mechanism is designed to constitute a part of a train control system wherein electro-magnetic flux along the track rails is responded to by proper electric instrumentalities on the locomotive or other controlled vehicle to open and close an electric circuit between a current source and an electro-pneumatic valve which, when energized, prevents the escape of train-pipe pressure; such electric installation also embodying a forestalling key and an auxiliary circuit between said current source and valve adapted to be closed by such key so that the person in charge of the locomotive may establish such auxiliary circuit and prevent the reduction of the train-pipe pressure and the application of the brakes. 25

The present invention consists in a control valve governed by an electro-pneumatic valve and an electro-pneumatic switch 30 adapted to be opened by the air escaping from the train pipe a predetermined length of time after the electro-pneumatic valve is de-energized and the control valve assumes its train-pipe pressure releasing position.

It also consists in the details of construction illustrated in the accompanying drawing and particularly pointed out in the claims.

The present invention is embodied in the combination of the electro-pneumatic valve, the control valve, the electro-pneumatic switch, the connections between them, and the attachments thereto. The drawing shows the several parts in the normal inoperative positions occupied when the train is running on clear track.

The electro-pneumatic valve 90, of well known construction and commonly known as an E. P. valve is adapted to cause reduction 50 of the air pressure within the control valve 89 of the brake system and within the casing

of this E. P. valve is a magnet 91 adapted to draw down its armature 92 from which a stem 93 extends down to the valve 94, which is held on its seat while the magnet 55 91 is energized.

When a train is to be moved under clear conditions, at which time the E. P. valve is energized, the engineer swings the handle of his train valve to permit air to fill the 60 brake pipe 96 and thus release the brakes. This causes a slow accumulation of pressure within the chamber 97 and along the valve stem 98 and through the passage 99 into the top of the cylinder 100 above the piston 65 101. Compressed air also flows through the passage 102 into the storage chamber 103, this passage being provided with a calibrated portion 104 to prevent the air from too rapidly rushing into this chamber 103 which 70 might result in a lack of pressure above piston 101.

This brake pipe pressure is less than the pressure within the main reservoir (not shown) to which a pipe 106 connects. Air 75 from the main reservoir flows into the cylinder 107 through this pipe 106 and a passage 108 which is calibrated to limit this flow of air. The piston 109 in the cylinder 107 is mounted on the valve stem 98 which carries 80 a smaller piston 110 and the valve 111. Stems 112 and 113 are in alinement with the stem 98 and the former carries valve 114 while the latter carries valve 115. Pressure from the spring 116 tends to move these last 85 named stems toward the piston 110, but so long as main reservoir pressure remains in cylinder 107, these last named valves are held in the positions shown in the drawing.

The piston 101 is attached to a valve stem 90 118 which extends through a slot in the valve stem 98. This stem 118 carries a valve 119, which normally closes the passage 120. A second cylinder 121 adjacent and preferably in alinement with the piston 101 contains a piston 122, normally held upward by the spring 123. This cylinder is formed with any desired number and type of openings 124 and the lower end of the stem 125 which connects to the piston 122 is attached 100 to the switch member 72 which connects the wires 71 and 73 when in the position shown.

When the magnet 91 of the E. P. valve is de-energized, air pressure in the chamber 126 lifts the valve 94 and permits air to flow from the cylinder 107 through passage 127 into chamber 128 and through passage 129 controlled by valve 130 to the pipe 131 and whistle 132 which sounds to indicate that this valve is de-energized. Should this pipe be blocked for any reason, the safety valve 133 will open and the escape of air therethrough will have the same effect upon the control valve.

Normally, the pressure in the cylinder 107 is that of the main air reservoir and in the chamber 97 that of the train pipe, which is lower than that in the cylinder 107. The piston 109 being the larger, it will be normally held in the position shown. When the E. P. valve is de-energized and air flows from the cylinder 107, the greater pressure in the chamber 97 forces the piston 109 and 110 to the right in the drawing, moving the valve 111 to its seat and thereby cutting off the connection between the train pipe and the cylinder 100 and the reservoir 103. The spring 116 presses the valve 115 on its seat closing the passage between the reservoir 135 and the atmosphere which is normally open by way of passage 136, chamber 137, along valve stem 113 and aperture 138. At the same time, the spring 116 moves the valve 114 from its seat and permits air to flow from reservoir 103 through passage 102, along stem 112, chamber 137, passage 136 and through calibrated opening 139 into chamber 135. It also permits air to flow from cylinder 100 to flow through passage 99, along stem 112 and through passage 136 to reservoir 135. The reservoir 103 is of such size that the air therein, mixed with the air from cylinder 100, requires an appreciable length of time to flow through opening 139 and therefore slows up the opening of valve 119.

The calibrated openings 104 and 139 are of such capacity that the reduction of the pressure in the cylinder 100 above the piston 101 will require a predetermined time interval before the pressure below this piston lifts the piston and the valve 119 connected thereto. This time interval is provided to permit the E. P. valve to be re-energized to forestall the application of the brakes, as will be explained later on. Should the E. P. valve remain de-energized beyond this predetermined time interval, the piston 101 and valve 119 will lift, and the train pipe air will rush through pipe 96 and passage 120 onto piston 122 in cylinder 121, forcing down this piston below the holes 124, which will permit the free discharge of the train line air. When this piston is forced down, the switch 72 is opened, and with it the circuit of wires 71 and 73. The rate of escape of air from the apertures 124 will always be greater than the rate at which air can be supplied to the train pipe

through the usual automatic brake valve so that the pressure in the train pipe will always be reduced to apply the brakes. This rate of reduction is controlled by the rate of reduction of pressure above the piston 101 and that in turn is controlled by the calibrated air valve 141 which allows air to escape from the reservoir 135 at a predetermined rate.

The pressure in the chamber 97 and on the piston 110 is therefore gradually reduced until the pressure within the cylinder 107 on the larger piston 109 is sufficiently greater to move these pistons and the valves to normal position. The pressure in cylinder 107 is derived from the pipe 106 wherein it is under high pressure, and the amount which passes through the restricted passage 108 is equal to the amount which can flow through valve 130 at the reduced pressure, and this pressure will therefore be fairly constant after valve 94 is lifted from its seat.

The pistons 109 and 110 and valves 111 and 114 are moved to normal position to stop the reduction of pressure above the piston 101 as soon as a partial and sufficient reduction of train pipe pressure has been made. But should the automatic brake valve be opened to admit air under pressure to the train pipe in order to release the brakes, or to feed the train pipe as this is termed, any increase in train pipe pressure from such admission will cause the pistons 109 and 110 to move to the right, in the drawing and the action of these parts as above described will be repeated.

The reduced pressure in the train pipe cannot therefore be augmented to release the brakes until the E. P. valve is again energized.

The action of this control valve is to cause but delay the lifting of the valve 119 and the opening of the auxiliary circuit to the E. P. valve which includes the wires 71, switch 72 and wire 73 until the pressure of the air above the piston 101 and within the reservoir 103 has been reduced sufficiently to permit this piston 101 to be lifted, which usually takes from 7 to 10 seconds, depending upon the size of the opening 139. If however, during such time the auxiliary circuit to the E. P. valve is closed before this time has elapsed, the re-energized E. P. valve will stop the escape of air from the cylinder 107 and the pressure therein will immediately build up and move the parts to the positions shown, the pressure which has been built up in the chamber 137 slowly escaping through the small valve 141. But should this auxiliary circuit not be closed until the valve 119 opens, train-pipe pressure will be released and the parts remain in pressure releasing position until the E. P. valve is re-energized by current received over the regular circuit.

The details of construction and the pro-

portions of the parts may all be changed by those skilled in the arts without departing from the spirit of our invention as set forth in the following claims.

5 We claim:

1. A brake control mechanism comprising a control-valve body embodying a chamber, a train-pipe connected thereto, a valve to permit the escape of air from said chamber, 10 a piston connected to said valve and a cylinder for said piston, said valve body being formed with passages connecting the chamber to the outer end of said cylinder so that the pressure therein will normally be equal 15 to that in said chamber, said valve body being formed with a pair of cylinders, pistons therein and a stem connecting them, a valve on said stem controlling said passages, a pipe connecting one of said last named 20 cylinders to a source of air under high pressure the other cylinder connecting to said chamber, and an electro-pneumatic valve preventing when energized the escape of said high pressure air, but when de-energized, 25 permitting the escape of said pressure to allow the pressure in said chamber to move said connected pistons and the valve connected thereto to permit the discharge of the pressure from the first named cylinder and 30 the discharge of said train-pipe pressure.
2. A brake control mechanism comprising a control-valve body embodying a chamber, a train-pipe connected thereto, a valve to permit the escape of air from said chamber, 35 a piston connected to said valve and a cylinder for said piston, said valve body being formed with passages connecting the chamber to the outer end of said cylinder so that the pressure therein will normally be equal 40 to that in said chamber, said valve body being formed with a pair of cylinders, pistons therein and a stem connecting them, a valve on said stem controlling said passages, a pipe connecting one of said last named cylinders to a source of air under high pressure 45 the other cylinder connecting to said chamber, and an electro pneumatic valve preventing when energized the escape of said high pressure air, but when de-energized, permitting 50 the escape of said pressure to allow the pressure in said chamber to move said connected pistons and the valve connected thereto to permit the discharge of the pressure from the first named cylinder and the discharge 55 of said train-pipe pressure, and means restricting the escape of air above said first named piston so the movement of the valve connected thereto may be delayed a predetermined period of time.
3. In a brake control mechanism, the combination with the train-pipe and a pipe connecting to a main storage reservoir of an air brake system, of a control valve body embodying two cylinders and pistons therein 60 and a stem connecting them, one of said cyl-
- inders being normally under train-pipe pressure and the second under main reservoir pressure, said pressures exerting opposing forces, a relief valve to permit the discharge of train-pipe pressure, means normally under train-pipe pressure to hold said valve on its seat, a normally energized electro-magnetic valve adapted when deenergized to release the pressure on said second piston to permit train-pipe pressure to move said pistons, and means actuated by said pistons to permit the release of said relief valve and the discharge of train-pipe pressure when said pistons are thus moved.
4. In an air brake controlling apparatus 80 of the character described, the combination of the train-pipe a normally energized electro-pneumatic valve, an automatic control valve movable by train-pipe pressure for producing a predetermined reduction in 85 train-pipe pressure when said electro-pneumatic valve is deenergized and for returning to normal position after such reduction, and of means responding to an increase in train-pipe pressure to again cause the control valve to function if such train-pipe pressure is increased while said electro-pneumatic valve is de-energized, the amount of 90 said reduction of train-pipe pressure being controlled by the difference in area of two 95 air passages, one leading to said control valve and the other leading therefrom to said electro-pneumatic valve.
5. In a brake control mechanism of the character described, the combination with the train-pipe, a normally energized electro-pneumatic valve, a control valve governed thereby, automatic means embodying said two valves for causing the reduction of pressure in said train-pipe when said electro-pneumatic valve is de-energized, an electric 100 switch, and means responding to the discharge of air from said train-pipe to open said switch.
6. In a brake control mechanism of the character described, the combination with the train-pipe, a normally energized electro-pneumatic valve, a control valve governed thereby, automatic means embodying said two valves for causing the reduction of pressure in said train-pipe when said electro-pneumatic valve is de-energized, an electric 105 switch, and means responding to the discharge of air from said train-pipe to open said switch and means for delaying the reduction of said train-pipe pressure by said automatic means a predetermined period after the electro-pneumatic valve is de-energized.
7. In a brake control mechanism of the character described, the combination with the train-pipe, a normally energized electro-pneumatic valve, a control valve governed thereby, automatic means embodying said two valves for causing the reduction of pressure 110

sure in said train-pipe when said electro-pneumatic valve is de-energized, an electric switch, and means responding to the discharge of air from said train-pipe to open 5 said switch and means for delaying the reduction of said train-pipe pressure by said automatic means a predetermined period after the electro-pneumatic valve is de-energized, comprising a reservoir wherein air is 10 stored under train-pipe pressure and a second reservoir connected to the atmosphere by a restricted passage into which second chamber the first chamber discharges.

8. In a brake control mechanism, the combination with the train-pipe and a pipe connecting to a main storage reservoir of an air 15 brake system, of a control valve body embodying two cylinders and pistons therein and a stem connecting them, one of said cylinders being normally under train-pipe pressure and the second under main reservoir pressure said pressures exerting opposing 20 forces, a relief valve to permit the discharge of train-pipe pressure, means normally under train-pipe pressure to hold said valve on its seat, a normally energized electro-magnetic 25 valve adapted when de-energized to release the pressure on said second piston to permit train-pipe pressure to move said pistons, 30 means actuated by said pistons to permit the release of said relief valve and the discharge of train-pipe pressure when said pistons are thus moved and a whistle adapted to be sounded by the air released by said electro-pneumatic valve.

9. In a brake control mechanism, the combination with the train-pipe and a pipe connecting to a main storage reservoir of an air 40 brake system, of a control valve body embodying two cylinders and pistons therein and a stem connecting them, one of said cylinders being normally under train-pipe pressure and the second under main reservoir pressure, said pressures exerting opposing 45 forces, a relief valve to permit the discharge of train-pipe pressure, means normally under train-pipe pressure to hold said valve on its seat, a normally energized electro-magnetic valve adapted when de-energized to release 50 the pressure on said second piston to permit train-pipe pressure to move said pistons, means actuated by said pistons to permit the release of said relief valve and the discharge 55 of train-pipe pressure when said pistons are thus moved, the sizes of the connected pistons and of the discharge passages from said second cylinder being such that the relief valve will be closed when the train-pipe pressure has been reduced a predetermined 60 degree.

10. In a brake control mechanism, the combination with the train-pipe and a pipe connecting to a main storage reservoir of an air 65 brake system, of a control valve body

embodying two cylinders of different diameters, connected pistons in said cylinders and a stem connecting them, the smaller piston being under train-pipe pressure and the larger piston under main reservoir pressure, said pressures acting oppositely; a relief 70 valve to permit the discharge of train-pipe pressure, a valve connected to said pistons to normally cause the relief valve to remain closed, and a normally energized electro-magnetic valve and passages controlled 75 thereby, which, when said electro-magnetic valve is de-energized, permit a partial reduction of pressure on said larger cylinder and permit the pistons to be moved by train-pipe pressure to cause the opening of the relief valve, said reduced pressure on the larger valve causing a return movement of the pistons when train-pipe pressure has been reduced a predetermined degree.

11. In a brake control mechanism, the combination with the train-pipe and a pipe connecting to a main storage reservoir of an air 80 brake system, of a control valve body embodying two cylinders of different diameters, connected pistons in said cylinders and a stem connecting them, the smaller piston being under train-pipe pressure and the larger piston under main reservoir pressure, said pressures acting oppositely, a relief 85 valve to permit the discharge of train-pipe pressure, a valve connected to said pistons to normally cause the relief valve to remain closed, and a normally energized electro-magnetic valve and passages controlled 90 thereby, which, when said electro-magnetic valve is de-energized, permit a partial reduction of pressure on said larger cylinder and permit the pistons to be moved by train-pipe pressure to cause the opening of the relief valve, said reduced pressure on the larger valve causing a return movement of the pistons when train-pipe pressure has been reduced a predetermined degree.

12. In a brake control mechanism, the combination with the train-pipe and a pipe connecting to a main storage reservoir of an air 95 brake system, of a control valve body embodying two cylinders of different diameters, connected pistons in said cylinders and a stem connecting them, the smaller piston being under train-pipe pressure and the larger piston under main reservoir pressure, said pressures acting oppositely, a relief 100 valve to permit the discharge of train-pipe pressure, a valve connected to said pistons to normally cause the relief valve to remain closed, and a normally energized electro-magnetic valve and passages controlled 105 thereby, which, when said electro-magnetic valve is de-energized, permit a partial reduction of pressure on said larger cylinder and permit the pistons to be moved by train-pipe pressure to cause the opening of the relief valve, said reduced pressure on the larger valve causing a return movement of the pistons when train-pipe pressure has been reduced a predetermined degree and means to delay the opening of the relief 110 valve a predetermined time after the connected pistons are moved by such train-line pressure.

13. In a brake control mechanism, the combination with the train-pipe and a pipe connecting to a main storage reservoir of an air 115 brake system, of a control valve body embodying two cylinders of different diameters, connected pistons in said cylinders and a stem connecting them, the smaller piston being under train-pipe pressure and the larger piston under main reservoir pressure, said pressures acting oppositely, a relief 120 valve to permit the discharge of train-pipe pressure, a valve connected to said pistons to normally cause the relief valve to remain closed and a normally energized electro-magnetic valve and passages controlled 125 thereby, which, when said electro-magnetic

valve is de-energized, permit a partial reduction of pressure on said larger cylinder and permit the pistons to be moved by train-pipe pressure to cause the opening of the relief valve, said reduced pressure on the larger valve causing a return movement of the pistons when train-pipe pressure has

been reduced a predetermined degree and an electro-pneumatic switch adapted to be opened by the force of the escaping train-pipe pressure when said relief valve is opened. ¹⁰
